ATTORNEY

UNITED STATES PATENT OFFICE

CLARENCE D. BARR, OF BIRMINGHAM, ALABAMA, ASSIGNOR TO SAND SPUN PATENTS CORPORATION, OF WILMINGTON, DELAWARE, A CORPORATION OF DELAWARE

FLASK

Application filed September 23, 1931. Serial No. 564,689.

My present invention relates to certain new and useful improvements in flasks for use in connection with centrifugal casting machines for casting hollow tubular bodies such as cast iron bell and spigot pipes for gas and water mains, and the like, although flasks made in accordance with the present invention may or may not have bell and spigot ends.

10 The flask of the present invention is constructed and designed for the manufacture of pipes of relatively large diameter as, for instance, a diameter of 14 inches and larger and of relatively long length, as for instance 16 feet or longer, although I do not wish to be understood as limiting myself as to the size.

15 Flasks of the type forming the subject matter of this application are usually provided with a refractory lining, such as a lining of appropriately rammed sand or sand mixtures, and the wall of the flask is perforated for venting purposes during the centrifugal casting operation.

20 Flasks of the kind referred to usually weigh a ton or more depending upon the size of the pipe to be made therein, and one of the objects of the invention is to provide a flask with means which will permit the same to be readily transported to and from the casting machine by an overhead crane and grapple, said means permitting the flask to be so manipulated that it may be readily stood on its end to permit the sand lining to be rammed therein and to permit the drying thereof and to enable the flask to be deposited in a horizontal position in the casting machine—it being understood that with flasks of this type a freshly prepared flask is employed with each cast.

25 Another object of the invention is to provide a flask for centrifugal casting machines that is made up of a plurality of sections so constructed and arranged that they may be easily assembled into a single unit and wherein any one of the flask sections may be readily renewed in the event of breakage or damage to such section, and without being compelled to discard an entire flask in

the event a portion thereof should be damaged.

30 A further object of the invention is to provide a flask of the type referred to with a novel construction of annular ring or track 55 constituting the supporting means for the flask when in position for rotation in the centrifugal casting machine.

To these and other ends the invention resides in the combinations and arrangement 60 of parts hereinafter described in detail and then more particularly pointed out in the appended claims.

35 In order to enable others skilled in the art to manufacture and use my said invention I will now proceed to describe the same in detail, reference being had for this purpose to the accompanying drawing, wherein,

40 Fig. 1 is a longitudinal section of a flask 70 made in accordance with the invention;

45 Fig. 2 is an end view looking into the spigot end of the flask;

50 Fig. 3 is a transverse section taken on the line 3—3 of Fig. 1; and

55 Fig. 4 is an end view looking into the bell end of the flask.

60 Referring more particularly to Fig. 1 of the drawing it will be seen that the flask consists of three separate sections, 1, 2 and 3, the section 1 being the spigot end, 2, the intermediate section, and 3 the bell end section which is outwardly flared both exteriorly and interiorly as shown.

65 The section 1 is provided at the end adjacent section 2 with an annular flange 4; the section 2 is provided at each end with an annular flange 5, and the section 3 is provided at its end adjacent section 2 with a flange 6. Between each of the sections 1 and 2 is arranged an annular T-shaped ring 7, the flange 8 of each ring fitting between the flanges of the sections 1, 2 and 3, the said flanged sections being connected to the rings 7, by means of bolts 9 or other suitable connecting means. The outer surface or rim of each ring 7 is truly cylindrical and presents a smooth circular surface to rest upon two pairs of flask-supporting rollers 100

(not shown) forming a part of the centrifugal casting machine.

I prefer to make the intermediate section 2 of the flask of cast iron and the two end 5 sections of cast steel. A reason for this is to give the flask greater strength at its ends where it is subjected to the greatest strains in the transportation thereof as hereinafter described and without likelihood of breakage.

The flask sections may be cast either centrifugally or otherwise, and I prefer to make the inner wall thereof gradually tapering outwardly from the spigot end toward the 15 bell end to facilitate the removal of the casting with its refractory sand lining, these being usually removed simultaneously by pushing the casting and its lining endwise of the flask by a suitable pushing plunger 20 and a pulling means (not shown).

Owing to the size and weight of the flask I prefer to transport them from the ramming station to the centrifugal casting machine and back to the pipe-extracting station by means of an overhead crane and suitable grapples, instead of rolling them on skids or tracks as is customary with the smaller and lighter flasks. To accomplish this I provide my flask with means at each 25 end thereof to receive suitable hooks or other grapples carried by and suspended from the overhead lifting and transporting crane.

As will be seen by referring to the drawing, I provide one end of the flask, namely, 30 the spigot end, with oppositely arranged outstanding trunnions 10, each trunnion being carried by a plate 12, which is secured to the flask by bolts or rivets 13, the free end of each trunnion being preferably flanged as at 40 14, to prevent the engaging hook from slipping endwise therefrom when brought into engagement therewith. I prefer to provide two pairs of oppositely arranged trunnions although in some instances I may employ 45 only one pair.

At the bell end of the flask I provide oppositely arranged plates 15, each having flanges 16, by which the plates may be bolted or riveted to the flask, and each plate is provided 50 with an eye or opening 17, to receive a supporting hook suspended from and carried by the overhead crane. When it is desired to transport the flask either toward or from the centrifugal casting machine, it is only necessary 55 to engage the suspended hooks with a pair of the trunnions 10, and a single hook in the eye or opening 17, of one of the plates 15, and lifting the flask a sufficient distance to remove it from the casting machine, it 60 may then be transported while maintained in the horizontal position, and due to the arrangement of the trunnions and eye plates, one end of the flask, as, for instance, the bell end, may be lowered while maintaining the 65 elevation or by raising the spigot end until

the flask assumes a perpendicular position, thus enabling it to be deposited in an upright or in any position desired. I prefer to provide the bell end of the flask with two pairs of oppositely arranged eye plates corresponding with the trunnions 10 at the opposite end of the flask so that irrespective of the position of the flask in the machine an eye plate and a pair of trunnions will be in position to be engaged by the grapples or carrying hooks.

The walls of the flask sections 12 and 13 are provided throughout their length with suitable vent openings which are usually counterbored at their outer ends, said openings serving to permit free venting of the flask during the centrifugal casting operation.

While I have illustrated and described a preferred embodiment of my invention, I do not wish to be understood as limiting myself to the specific construction shown except as I may be limited by the terms of the appended claims, as obviously changes may be made without departing from the spirit of the invention.

What I claim is:

1. A flask for use in centrifugal casting machines, comprising an intermediate and end sections, and cylindrical tread rings connecting said sections in end-to-end relationship, the outer surface of said rings constituting supporting treads.

2. A flask for use in centrifugal casting machines, comprising an intermediate and end sections and a pair of flanged tread rings connecting said sections in end-to-end relationship, each of said rings having a cylindrical outer surface constituting a supporting tread.

3. A flask for use in centrifugal casting machines, comprising an intermediate and end sections arranged in end-to-end relationship, each section having an annular flange and flanged tread rings connecting said sections, each ring having a cylindrical outer surface constituting a supporting tread.

4. A flask for use in centrifugal casting machines comprising a cast iron intermediate section and cast steel end sections, and tread rings connecting said sections in end-to-end relationship, said rings each having a cylindrical outer surface constituting supporting treads.

5. A flask for use in centrifugal casting machines comprising an intermediate and end sections, and connecting tread rings substantially T-shaped in cross sections connecting said sections in end-to-end relationship, each ring having a cylindrical outer surface constituting a support tread.

6. A flask for use in centrifugal casting machines comprising an intermediate section, a bell section, and a spigot section, annular tread rings at the adjacent ends of said

- sections and means for connecting the said rings and sections, each ring having an outer cylindrical surface constituting a tread for rolling contact with supporting rollers.
- 5 7. A flask for use in centrifugal casting machines, comprising an intermediate and end sections arranged end to end, each section having an annular flange, annular rings between the adjacent ends of said sections,
- 10 each ring having a cylindrical tread rim overlying its associated flanges and a web located between the flanges, and means for connecting the flanges and webs, said tread rims adapted to support the flask for rotation.
- 15 8. A flask for use in centrifugal casting machines, comprising an intermediate and end sections, cylindrical tread rings connecting said sections in end-to-end relationship, the outer surface of each ring constituting
- 20 a supporting tread, oppositely-disposed trunnions at one end of the flask and outwardly extending apertured plates at the other end, said trunnions and plates constituting means for engagement by trans-
- 25 porting grapples.

Signed at Birmingham in the county of Jefferson and State of Alabama this 17th day of September A. D. 1931.
